UNITED STATES PATENT OFFICE.

LEWIS C. BAYLES, OF EASTON, PENNSYLVANIA, AND GROVER G. TUTTLE, OF PHILLIPSBURG, NEW JERSEY, ASSIGNEES TO INGERSOLL-RAND COMPANY, OF JERSEY CITY, NEW JERSEY, A CORPORATION OF NEW JERSEY.

STEEL RETAINER.

Application filed August 30, 1927. Serial No. 216,398.

This invention relates to rock drills, but more particularly to steel retainers adapted to be applied to the front end of a hammer type rock drill.

5 One object of the invention is to prevent removal of the steel from the front head while the steel is being withdrawn from the drill hole.

Another object is to prevent ejection of 10 the steel from the front head while the drill is in operation and a further object is to produce a rugged steel retainer having few parts which are inexpensive to manufacture, efficient in operation and which may be readily 15 assembled and disassembled.

Other objects will be in part obvious and in part pointed out hereinafter.

The invention consists of the combination 20 of elements and arrangement of parts having the general mode of operation herein-after described and pointed out more particularly in the appended claims and illustrated in the accompanying drawings, in which

25 Figure 1 is a sectional view in elevation of so much of a rock drill as will serve to illustrate the invention.

Figure 2 is a plan view of the front end of 30 a rock drill partly in section, the section being taken on the line 2—2 looking in the direction indicated by the arrows, and

Figure 3 is an end view of a rock drill looking from the front end.

Referring to the drawings, the invention 35 is shown applied to a rock drill having a cylinder A in which is mounted a reciprocating hammer piston B. The front end of the cylinder A is closed by a front cylinder washer C. Surrounding the front end of the 40 hammer piston B is a chuck D in the front end of which is secured a chuck bushing E. A front head F is held in place by the usual side bolts G passing through lugs H and having nuts J securely held in place by lock nuts K and lock washers L. Interposed between the lugs H and the nuts J are springs O. Extending into the front head F is a drill steel or working implement P having a collar Q'.

50 In the operation of a pneumatic tool of the type described, it is necessary to provide means for retaining the working implement in the front head. In the present invention the working implement is retained by the

device described in the following paragraphs:

An enlargement Q is formed on the front end of the front head F. In the front of this enlargement is formed a cylindrical opening R having one side cut away as shown at S. 60 A cap T having its outer cylindrical surface U of such a size that it fits snugly in the opening R is provided with a handle V and an inner cylindrical bore W concentric with its outer cylindrical surface. This bore W does 65 not pass completely through the cap T but is so formed as to leave an end wall X of substantial thickness. Through the end wall X is formed a bore Y suitable for the passage of a bolt Z. The bolt Z has a head 70 b and a shank c. Near the headless end of the bolt Z is formed an aperture d transverse to the axis of the bolt.

At its rearward end, the cylindrical opening R is reduced to form an aperture e of 75 such a size that the bolt Z will fit snugly therein. Two notches f and g are formed in the front periphery of the front head enlargement Q. Passing through the front head enlargement Q is an aperture h transverse to the axis of the bolt Z. There is provided a key j of suitable size to pass through the aperture h in the front head enlargement Q and the aperture d in the bolt Z, the key having a notch j' cut in its upper edge. 80

85 The operation of the steel retainer is as follows: Assuming that the operator wishes to insert a drill steel into the tool, he first places a drill steel shank k into the chuck bushing E. This operation is followed by 90 inserting the cap T into the cylindrical opening R. He then places a helical spring o around the shank of the bolt Z and inserts the bolt Z into the aperture e.

He next places the bolt head b in such a 95 position that when his weight is thrown upon the handle of the rock drill, the spring o will be compressed forcing the bolt Z into the hole e far enough so that the key j may be inserted through the apertures h and c. 100 This securely locks the cap T, springs o and bolt Z in place. It will be noticed, however, that the aperture d has its length slightly greater than the breadth of the key j. This is to permit a slight amount of play or longitudinal movement between the bolt Z and its aperture e.

The cap T is cut away as shown at p to per-

mit the collar Q' of the drill steel P to pass when the drill steel is being inserted or extracted from the front head F. Once the drill steel has been inserted, all that is necessary to retain it in a working position is to turn the handle V to the position shown by the broken line at V'. This operation of turning the handle moves the cut-away portion p to the position shown by the broken line p'.
10 The construction of the steel in the manner herein described provides a very substantial and rugged retainer. The key j is designed so that its shearing strength will be equal to the tensile strength of the bolt Z.
15 When the collar Q' of the drill steel P is driven against the upper edge of the cap T, this edge will be burred to some extent. To provide for easy turning of the cap T after this burring effect has taken place, an annular groove r is formed around the upper end of the cylindrical surface R. Leading into this groove r is an oil hole s which is provided to keep the moving parts of the retainer well oiled at all times.
20 It will be noticed that during the operation of the tool, a constant vibration occurs and an occasional blow from the collar W of the drill steel P upon the edge y of the cap T. To prevent the cap T from being displaced so that the groove p might come into the position shown in Figure 3 and permit the drill steel P to be ejected from the front head, the notches f and g are cut in the front part of the projection Q. The spring o exerts a constant pressure against the cap T forcing it upward and for this reason the handle V will be securely held in the position in which it was placed by the operator regardless of the vibration of the tool.
25

40 We claim:

1. In a pneumatic tool, the combination of a front head having a bore adapted to receive the collared shank of a drill steel and having an enlarged front end portion formed with a cylindrical recess, a cap in said recess, means for securing said cap in place, a groove in said cap adapted to permit the passage of a drill steel collar into or out of said front head bore, said cap adapted to be rotated to bring said groove into or out of registry with the periphery of said front head bore to permit or

prevent the passage of said drill steel collar into or out of said front head bore.

2. In a pneumatic tool, the combination of a front head having a bore adapted to receive the collared shank of a drill steel and having an enlarged front end portion with a cylindrical recess formed therein, a cap in said recess, means for securing said cap in place, resilient means to absorb the impact of the drill steel collar upon said cap, a groove in said cap and means for rotating said cap to different positions to bring said groove into or out of registry with the periphery of said front head bore to permit or prevent the passage of said drill steel collar into or out of the said front head bore.

3. In a pneumatic tool, the combination of a front head having a bore adapted to receive the collared shank of a drill steel and having an enlarged front end portion with a cylindrical recess formed therein, a cap in said recess, means for securing said cap in place, resilient means to absorb the impact of the drill steel collar upon said cap, a groove in said cap, means for rotating said cap to different positions to bring said groove into or out of registry with the periphery of said front head bore to permit or prevent the passage of said drill steel into or out of the said front head bore, and means for locking said cap in position.

4. In a pneumatic tool, the combination of a front head having a bore adapted to receive the collared shank of a drill steel and having an enlarged front end portion with a cylindrical recess formed therein, a cap in said recess, means for securing said cap in place, said means comprising a bolt, an aperture through the shank of said bolt, and a key passing through an aperture in said front head and through the aperture in said bolt, resilient means disposed in said cap between said cap and the head of said bolt, said resilient means absorbing blows of said drill steel and cooperating with said key to hold the bolt in position.

55 In testimony whereof we have signed this specification.

LEWIS C. BAYLES.
